US00D871340S

(12) **United States Design Patent** (10) **Patent No.:** **US D871,340 S**
(45) **Date of Patent:** **** Dec. 31, 2019**

(54) **MODULE LATCH ACTUATOR**

(71) Applicants: **TE CONNECTIVITY NEDERLAND B.V.**, 'S-Hertogenbosch (NL); **TYCO ELECTRONICS SVENSKA AB**, Upplands Väsby (SE); **TYCO ELECTRONICS (SHANGHAI) CO., LTD.**, Shanghai (CN)

(72) Inventors: **Rickard Barrefelt**, Stockholm (SE); **Tekke Drijfhout**, Nistelrode (NL); **Johan Smits**, Biezenmortel (NL); **Zhicheng Zhang**, Kunshan (CN)

(73) Assignees: **TE Connectivity Nederland B.V.**, 'S-Hertogenbosch (NL); **Tyco Electronics Svenska AB**, Upplands Väsby (SE); **Tyco Electronics (Shanghai) Co., Ltd.**, Shanghai (CN)

(**) Term: **15 Years**

(21) Appl. No.: **29/555,478**

(22) Filed: **Feb. 22, 2016**

OTHER PUBLICATIONS

Extended European search report dated Jun. 15, 2016 for counterpart European application 16153472.2.

Primary Examiner — Angela J Lee
Assistant Examiner — Shawn T Gingrich

CLAIM

The ornamental design for module latch actuator, as shown and described.

DESCRIPTION

FIG. 1 is a top perspective view from the right side of a module latch actuator showing an embodiment of our new design;

FIG. 2 is a top perspective view from the left side thereof; FIG. 3 is a bottom perspective view from the right side thereof;

FIG. 4 is a bottom perspective view from the left side thereof; and,

FIG. 5 is a view of the rear side thereof.

The broken lines in the figures represent unclaimed subject matter and form no part of the claimed design.

1 Claim, 5 Drawing Sheets
